UNITED STATES PATENT OFFICE

102,072

DESIGN FOR A MASSAGE ROLLER

Kate P. Woodside, Greenville, S. C.

Application April 20, 1936, Serial No. 62,224

Term of patent 7 years

To all whom it may concern:

Be it known that I, Kate P. Woodside, a citizen of the United States, residing at Greenville, in the county of Greenville and State of South Carolina, have invented a new, original, and ornamental Design for a Massage Roller, of which the following is a specification, reference being had to the accompanying drawing in which:—

I claim:—

The ornamental design for a massage roller, as shown.

KATE P. WOODSIDE,
